REGISTER CONTROL MECHANISM FOR
PRINTING PRESSESHermann Kott, West Orange, N. J., assignor, by
mesne assignments, to Publication Corporation,
New York, N. Y., a corporation of New York

Application February 21, 1942, Serial No. 431,775

10 Claims. (Cl. 271—2.6)

The present invention relates to register control mechanisms for printing presses and embodies, more specifically, an improved form of mechanism by means of which the register of a continuous moving web of paper with respect to two or more cylinders may be effectively accomplished.

In my co-pending application Serial No. 211,365 there is described a web register mechanism utilizing a high frequency alternating carrier current as a force by means of which impulses that are in synchronism with the movement of the web may be impressed upon a remote electro-responsive device. The aforesaid impulses are utilized to modulate the carrier current and, in this fashion, the seriously objectionable time lag that would otherwise be occasioned by the low capacitance characteristic of the circuits is avoided.

In the aforesaid co-pending application, the impulses or modulations which are in synchronism with the occurrence of the spot previously applied to the web as an indexing or register marking, are utilized as a means for varying another force that is varied in accordance with the rotation of the printing cylinder, that is, the said other force is in synchronism with the cylinder rotation, and by combining these two forces in a suitable electro-responsive device, the desired indication of register with respect to the cylinder is accomplished.

Register mechanisms for low speed printing presses have heretofore been developed that function quite satisfactorily, but the extremely short intervals of time within which an impulse is available by reason of the presence of an indexing spot under the photoelectric cell has limited the extent of use to which these earlier web register mechanisms can be put.

The problem, accordingly, is to provide a system of the above general character which is capable of producing a sufficiently strong electrical impulse or current to accomplish the desired actuation, without introducing time lags and thus providing the desired operation within the extremely limited time interval available. An object of the present invention, accordingly, is to provide a web register mechanism for devices of the above character, the mechanism enabling a sufficiently strong current to be generated to effect the operation of a suitable electro-responsive mechanism and in the extremely limited interval of time available for such actuation.

A further object of the invention is to provide an improved mechanism of the above character

by means of which control mechanism may be actuated automatically to compensate for conditions of faulty register during registration.

5 A further object of the invention is to provide improved electrical mechanism by means of which a suitable alternating carrier current may be generated and modulated by spot occurrence to provide impulses of suitable strength and in synchronism with the spot occurrence, thus to permit desired controlling operations to be effected.

10 A further object of the invention is to provide an improved control mechanism by means of which the impulses above referred to and in synchronism with the spot occurrence may be utilized as a means for operating suitable corrective mechanism under predetermined conditions.

15 Further objects of the invention will be apparent as it is described in greater detail in connection with the accompanying drawings, wherein:

Figure 1 is a diagrammatic illustration of a web register control mechanism constructed in accordance with the present invention; and

20 Figure 2 is a diagrammatic illustration of a continuous web printing press on which the timing switch and light responsive mechanism have been installed in accordance with the present invention.

25 Referring to the aforesaid drawings, a lamp 1 supplies light to a condenser lens system 2 to direct a beam of light 3 to a rotating disc 4. The disc 4 is formed with a plurality of apertures 5 adjacent the periphery thereof, the disc and light being so arranged that the beam is focused at the path of the rotating apertures 5. Rotation of the disc 4 thus chops up the beam of light and provides a source of intermittent light impulses for beams 6 which are directed to an objective lens system 7 which focuses the beam upon the moving web W. The web has had printed upon it spots S, these spots having been printed by a printing cylinder P that has printed an impression which is to register with subsequently printed impressions. The spots thus pass under the light beam 6 in a common path so that the intermittent beam of light falls upon the spots as they pass beneath the beam.

30 Light is reflected from the web W in the form of a beam 8 and falls upon a photoelectric cell 9 of improved structure. This photoelectric cell or tube is formed to multiply the strength of the current generated by the tube. The tube 9 thus has a cathode 10 upon which the reflected beam 8 falls. The cathode 10 emits electrons which fall upon a series of dynodes that are placed with-

in the tube. For example, dynodes d^1 , d^2 , d^3 , d^4 , d^5 , d^6 , d^7 , d^8 and d^9 are mounted within the tube 3 and connected to resistances r^1 , r^2 , r^3 , r^4 , r^5 , r^6 , r^7 , r^8 , and r^9 , respectively, by means of wires a^1 , a^2 , a^3 , a^4 , a^5 , a^6 , a^7 , a^8 , and a^9 , respectively.

The aforesaid resistances are connected to wires 11 and 12 which are connected to a source of 1000 volt direct current. The resistances are so constructed that the voltage differential between the respective dynodes is 100 volts and, in this fashion, electrons emitted by the cathode 10 when light impinges upon it fall upon dynode d^1 and dislodge other electrons in a number that is a multiple of the electrons emitted by the cathode 10. These electrons, plus the additional dislodged electron from the dynode d^1 , fall upon the dynode d^2 and the operation is repeated. In this fashion, great amplification is accomplished so that the electrons falling upon the anode 13 result in the accomplishment of a large current in the wire 14.

It will be seen that the wire 11 is grounded at 15 to furnish a common ground wire for the circuit, and, in operation, the disc 4 is rotated at a sufficiently high speed to provide at least two light impulses upon the spot S as it travels beneath the beam of light 6. For example a frequency of 2500 impulses per minute has been found suitable for this purpose and the number of apertures 5 and the speed of rotation of the disc 4 can thus be easily determined.

By means of the foregoing mechanism, a very feeble current produced by a weak illumination can easily be multiplied several hundred thousand times so that the resultant output current of the tube affords a strong current which, for frequencies up to 100,000 cycles is a linear function of the exciting illumination, and the action of the tube is instantaneous.

The modulated carrier current furnished by the wire 14 is impressed across the primary of a transformer T, the other terminal of the primary being connected to ground by wire 16. The transformer T is provided with two secondaries 17 and 18 which are connected to detector tubes 19 and 20, respectively, by wires 21 and 22. The other terminals of the secondaries are connected to the cathodes of the detector tubes 19 and 20 by means of a wire 23 through a variable resistance 24, which, for example, may be 10,000 ohms. A condenser 25 which may be of 25 microfarads is connected across the resistance, and there is thus provided a grid bias adjustment so that the detector tubes can be adjusted for cut-off. The plates of the detector tubes are connected to ground at 15 by conductor 11 and through a condenser 26 which may be of .001 microfarad capacity and by means of wires 27 and 28, are connected to a resistance 29 that may be of about 10,000 ohms. A separate voltage supply 31 is connected across the resistance 29 by means of wires 31 and 32 and the resistance 29 is then connected by means of a wire 33 to the grid of an output amplifier tube 34. The wires 32 and 33 are connected to ground through a resistance 35 which may be of 20,000 ohms, this resistance serving as a low plate resistance for the detectors 19 and 20. The filament of the output amplifier 34 is connected to ground through a normal biasing resistance 36 and wire 31. The screen grid of the output amplifier is connected to ground through a wire 38, a resistance 39, wire 40 and condenser 41. The resistance 39 may be of about 30,000 ohms.

A plate voltage is supplied from a suitable source 42 which is grounded by a wire 43 and con-

nected by a wire 44 to a resistance 45 which is connected to the plate of the amplifier by means of a wire 46. The resistance 45 may be of 2500 ohms and the output of the amplifier is supplied through a wire 47 to a condenser 48. From the condenser 48, the current flows through a wire 49 to a phase inverter mechanism comprising tubes 50 and 51, the grids of which are connected across a Wheatstone bridge arrangement of resistances 52, 53, 54 and 55. The resistances are grounded at 56 and it has been found that good results are obtained by using 10,000 ohms for resistances 52 and 53 and 250,000 ohms for resistances 54 and 55.

The filaments of the inverter tubes 50 and 51 are grounded at 57 through an adjustable resistance 58 which enables the inverter tubes to be adjusted at cut-off by adjusting the grid bias 58, so that the inverter tubes are set at their maximum operating current, that is, with a sharp cut-off, the impulse from the amplifier causing a positive current to be produced in the output of the phase inverter.

This positive current is supplied by means of wires 59 and 60 to the grids of switching tubes 61 and 62. Each of the wires 59 and 60 is connected to a source of current 63 through a wire 63', this current being about a 400-volt direct current, resistances 64 and 65 being connected between the respective wires 59 and 60 and the said source of current. These resistances 64 and 65 are preferably of about 100,000 ohms.

Condensers 66 and 67 are connected between the output wires 59 and 60 and the plates of the inverter tubes 50 and 51 and corresponding resistances 64 and 65. These condensers are preferably of about .005 microfarad capacity.

Switching tubes 61 and 62 are adjusted so that they are operating at about their maximum operating current and are at sharp cut-off. This is accomplished by the bias resistances 68 and 69, respectively, for the tubes 61 and 62. The resistances 68 and 69 are connected to resistances 70 and 71, respectively by the respective wires 72 and 73, the resistances 70 and 71 being connected to a common resistance 74 which is connected to a source of high voltage current 75, grounded at 76. Resistances 70 and 71 are preferably of about 500,000 ohms and resistance 74 of about 250,000 ohms, the source of high voltage current being at a voltage of about 250 volts. As long as the grids of the switching tubes have this high voltage applied to them, the tubes are inoperative to respond to the voltages impressed upon them from the inverter tubes 50 and 51, since the switching tubes are operating at cut-off. The wires 59 and 60 are connected to the high voltage source of electricity 75 through a wire 77 and resistances 78 and 79. The resistances 78 and 79 are preferably of about 500,000 ohms.

The filaments of the switching tubes are grounded at 80 through wire 81 and the plates of the tubes are connected to output wires 82 and 83, respectively, these wires being connected through resistances 84 and 85, respectively, to a wire 86 and condenser 87 to the ground 80. The resistances 84 and 85 are connected to the source of current 63 through a wire 88 and a resistance 89. The resistances 84 and 85 are each of about 50,000 ohms, while the resistance 89 is of about 25,000 ohms.

The output wires 82 and 83 are connected respectively to condensers 90 and 91, each being of about .005 microfarad capacity. Wires 92 and 93 connect the condensers 90 and 91 through resistances 94 and 95 to thyratron tubes 96 and 97,

respectively. The resistances 84 and 85 are about 250,000 ohms and are connected to ground 88 through resistances 89 and 100, respectively, the resistances 89 and 100 being of about 100,000 ohms.

The filaments of the thyratron tubes 86 and 87 are connected to ground 88 through a resistance 101, which is of about 1000 ohms, the output wires 102 and 103 of the respective tubes 86 and 87 being connected to relay coils 104 and 105, respectively, the common terminals of the relay coils being connected to a source of 110-volt alternating current 106 and to a resistance 107 that is connected to the resistance 101. The resistance 107 is of about 8000 ohms. Relay coil 104 serves to actuate contacts 108 while coil 105 actuates contacts 109, the contacts being connected to a motor control circuit 110 which is of known structure, in order to operate a reversing motor so that a suitable accelerating or decelerating force may be applied to the moving web, thus to bring it into register with the printing cylinder.

A timing switch 111 is provided with forward and reverse conducting segments 112 and 112', respectively. These segments are separated by a dead segment 113 and a contact arm 114 moves over the segments in synchronism with the rotation of the printing cylinder which prints the second impression on the web. To accomplish this, the shaft upon which the contact arm 114 is mounted may be coupled directly to the printing cyl'nder, or, if desired, it may be rotated in synchronism therewith in any desired fashion. The contact arm 114 is grounded at 115 and the forward segment 112 is connected to wire 73 by means of a w're 116, while the reverse segment is connected to the wire 72 by means of a wire 117. In this fashion, the forward and reverse segments will be seen to be connected respectively to the gr'ds of the switching tubes 62 and 61. Thus, if the web is out of register with the printing cyl'nder, an impulse from the phase inverter will occur while either the forward or reverse segment is grounded by the movable contact arm 114. In this circumstance, the appropriate switching tube is thus subject to the operating impulse from the phase inverter tube. For example, if the contact arm 114 engages forward segment 112, the grid bias current of the tube 62 is grounded and the tube will no longer be operating at cut-off. The impulse, occurring under these circumstances, causes the output of the tube 62 to be impressed upon the thyratron tube 87 to actuate the relay coil 105.

A corresponding operation takes place w'th the switching tube 61 and thyratron tube 86 when the movable contact 114 engages segment 112'.

In operation, there is a normal grid voltage of about 1½ volts applied to the switching tubes 61 and 62 to make them operative. This is accomplished through the resistances 68 and 69 and an impulse in the output c'ircuits of the switching tubes is thus prevented, which impulse would operate the corresponding thyratron tubes. This impulse would arise from the 400 volt direct current supply 63.

In operation, the resistance 74 is of great importance. It serves as a buffer resistance to keep resistances 70 and 71 stable and prevent the grounding of one to be reflected in the other, causing oscillation.

Also, in operation, the resistances 64 and 65 are set so that the output of the phase inverter never exceeds about 50 volts.

Returning to the photoelectric mechanism, in-

asmuch as the mechanism is connected to an inductance in the form of the transformer T, the periodic current impulses generated produce an alternating current in accordance with the well-known electrical principles. The modulation of the amplitude of this alternating carrier current by the spot occurrence is such that when the spot occurs, the amplitude of the carrier current is decreased. In this fashion, the right-hand end 10 of the resistance 29 becomes more negative and the output of the amplifier decreases correspondingly. In other words, the output of the amplifier simultaneously becomes more negative. Thus, when there is a decreasing amplitude in the 15 photoelectric scanner circuit, there is an increasing amplitude in the output of the amplifier tube 34 although it is increasing on a negative cycle. The amplifier tube is always acting on its negative cycle and, with the phase inverter tube, there- 20 is produced a corresponding positive current in the output of the inverter.

It will be seen that the grids of the switching tubes are biased by two grid voltages, one for normal operation and one for operation below cut-off. The grid voltage which cuts the tube off is grounded and thus rendered ineffective by the contact arm 114 which rotates in synchronism with the printing cylinder. If the impulse is in register with the arrival of the arm 114 at the dead segment 113, the tube is inoperative because of the high negative cut-off voltage applied thereto. The leading or the lagging of the color mark on the web with respect to the arrival of the contact arm 114 at the dead segment will remove the high grid voltage applied to the switching tube and permit the impulse to pass to the corresponding thyratron tube to effect the desired compensating action.

I claim:

1. Web register mechanism for use with machines having means for feeding a continuous web having register spots applied thereto to a rotating cylinder for performing an operation on the web in predetermined relation to the register spots, said mechanism comprising a first electrical circuit, a photoelectric device in said circuit responsive to the occurrence of a spot to produce current changes in the circuit in synchronism with the spot occurrence, an electro-responsive device connected electrically with the photoelectric device, means connected electrically with the electro-responsive device normally to prevent actuation thereof by the said current changes in the circuit of the photoelectric device, a second circuit, mechanical means moved in synchronism with the rotation of the cylinder for connecting said second circuit with the means to prevent actuation of the electro-responsive device to render the electro-responsive device responsive to current changes in the first circuit.

2. Web register mechanism for use with machines having means for feeding a continuous web having register spots applied thereto to a rotating cylinder for performing an operation on the web in predetermined relation to the register spots, said mechanism comprising a first electrical circuit, a photoelectric device in said circuit responsive to the occurrence of a spot to produce current changes in the circuit in synchronism with the spot occurrence, an electro-responsive device connected electrically with the photoelectric device, thermionic means connected electrically with the electro-responsive device normally to prevent actuation thereof by the said current changes in the circuit of the photoelectric de-

vice, a second circuit, and mechanical means moved in synchronism with the rotation of the cylinder connecting said second circuit with the means to prevent actuation of the electro-responsive device to render the electro-responsive device responsive to current changes in the first circuit.

3. Web register mechanism for use with machines having means for feeding a continuous web having register spots applied thereto to a rotating cylinder for performing an operation on the web in predetermined relation to the register spots, said mechanism comprising an electrical circuit, a photoelectric device in said circuit responsive to the occurrence of a spot to produce current changes in the circuit in synchronism with the spot occurrence, an electro-responsive device connected electrically with the photoelectric device, thermionic means connected electrically with the electro-responsive device normally to prevent actuation thereof by the said current changes in the circuit of the photoelectric device, a contact member having conducting segments spaced upon opposite sides of a non-conducting segment, wires connecting the contact members to the thermionic means, and a contact arm moving in synchronism with the rotation of the cylinder and engaging the said segments, said contact arm having an effective contacting face shorter than the non-conducting segment.

4. Web register mechanism for use with machines having means for feeding a continuous web having register spots applied thereto to a rotating cylinder for performing an operation on the web in predetermined relation to the register spots, said mechanism comprising a first electrical circuit, a photoelectric device in said circuit responsive to the occurrence of a spot to produce current changes in the circuit in synchronism with the spot occurrence, an electro-responsive device connected electrically with the photoelectric device, two thermionic tubes connected electrically with the electro-responsive device normally to prevent actuation thereof by the said current changes in the circuit of the photoelectric device, means normally to bias said tubes at cut-off, a second circuit, and mechanical means moved in synchronism with the rotation of the cylinder for connecting said second circuit with the said normal biasing means to change the aforesaid bias to render the tubes operative to permit actuation of the electro-responsive device by the said current changes.

5. Web register mechanism for use with machines having means for feeding a continuous web having register spots applied thereto to a rotating cylinder for performing an operation on the web in predetermined relation to the register spots, said mechanism comprising an electrical circuit, a photoelectric device in said circuit responsive to the occurrence of a spot to produce current changes in the circuit in synchronism with the spot occurrence, an electro-responsive device connected electrically with the photoelectric device, two thermionic tubes connected electrically with the electro-responsive device normally to prevent actuation thereof by the said current changes in the circuit of the photoelectric device, means normally to bias said tubes at cut-off, a conducting segment connected to the grid of each of the said tubes and spaced upon opposite sides of a non-conducting segment, and a contact arm having an effective contacting face shorter than the non-conducting segment and moving in synchronism with the rotation of the

cylinder and connected to change the bias of the grids of the respective tubes to render the tubes operative to permit actuation of the electro-responsive device by the said current changes.

5 6. Web register mechanism for use with machines having means for feeding a continuous web having register spots applied thereto to a rotating cylinder for performing an operation on the web in predetermined relation to the register spots, said mechanism comprising a first electrical circuit, a photoelectric device in said circuit responsive to the occurrence of a spot to produce current changes in the circuit in synchronism with the spot occurrence, two electro-responsive devices connected electrically with the photoelectric device, thermionic tubes connected electrically with the respective electro-responsive devices, means to bias the grids of the said tubes at cut-off normally to prevent actuation of the said electro-responsive devices by the said current changes in the circuit of the photoelectric device, a second circuit, and mechanical means moved in synchronism with the rotation of the cylinder for connecting said second circuit with the said normal biasing means to change the grid bias of the said tubes to permit the electro-responsive devices to be actuated by the said current changes.

30 7. Web register mechanism for use with machines having means for feeding a continuous web having register spots applied thereto to a rotating cylinder for performing an operation on the web in predetermined relation to the register spots, said mechanism comprising a first electrical circuit, a photoelectric device in said circuit responsive to the occurrence of a spot to produce current changes in the circuit in synchronism with the spot occurrence, two electro-responsive devices connected electrically with the photoelectric device, thermionic tubes connected electrically with the respective electro-responsive devices, electric circuits including resistances to bias the grids of the said tubes at cut-off normally to prevent actuation of the said electro-responsive devices by the said current changes in the circuit of the photoelectric device, a ground circuit, and mechanical means moved in synchronism with the rotation of the cylinder for connecting the ground circuit to the biasing circuit to ground the resistances to permit the electro-responsive devices to be actuated by the said current changes.

45 8. Web register mechanism for use with machines having means for feeding a continuous web having register spots applied thereto to a rotating cylinder for performing an operation on the web in predetermined relation to the register spots, said mechanism comprising an electrical circuit, a photoelectric device in said circuit responsive to the occurrence of a spot to produce current changes in the circuit in synchronism with the spot occurrence, two electro-responsive devices connected electrically with the photoelectric device, thermionic tubes connected electrically with the respective electro-responsive devices, electric circuits including resistances to bias the grids of the said tubes at cut-off normally to prevent actuation of the said electro-responsive devices by the said current changes in the circuit of the photoelectric device, a resistance in series with the first named resistance, and mechanical means moved in synchronism with the rotation of the cylinder for grounding the first named resistances to permit the electro-responsive devices to be actuated by the said current changes.

75 9. Web register mechanism for use with ma-

chines having means for feeding a continuous web having register spots applied thereto to a rotating cylinder for performing an operation on the web in predetermined relation to the register spots, said mechanism comprising a first electrical circuit, a photoelectric multiplying device in said circuit responsive to the occurrence of a spot to produce current changes in the circuit in synchronism with the spot occurrence, said photoelectric device having an anode and a cathode 10 connected in said circuit and a plurality of multiplying dynodes to multiply the electronic discharge reaching the anode, an electro-responsive device connected electrically with the photoelectric device, means connected electrically with the 15 electro-responsive device normally to prevent actuation thereof by the said current changes in the circuit of the photoelectric device, a second circuit and mechanical means moved in synchronism with the rotation of the cylinder for connecting said second circuit with the means to prevent actuation of the electro-responsive device to render the electro-responsive device responsive to current changes in the first circuit.

10. Web register mechanism for use with machines having means for feeding a continuous

5 web having register spots applied thereto to a rotating cylinder for performing an operation on the web in predetermined relation to the register spots, said mechanism comprising a first electrical circuit, a photoelectric multiplying device in said circuit responsive to the occurrence of a spot to produce current changes in the circuit in synchronism with the spot occurrence, said photoelectric device having an anode and a cathode 10 connected in said circuit and a plurality of multiplying dynodes to multiply the electronic discharge reaching the anode, means to impress voltages of different magnitudes on the respective dynodes, an electro-responsive device connected electrically with the photoelectric device, means connected electrically with the electro-responsive device normally to prevent actuation thereof by the said current changes in the circuit of the photoelectric device, a second circuit, and mechanical means moved in synchronism with the rotation of the cylinder for connecting said second circuit with the means to prevent actuation of the electro-responsive device to render the electro-responsive device responsive to current changes in the first circuit.

20 25 HERMANN KOTT.
